AUTOMOBILE RAIN GUARD FOR DRIVE-IN THEATERS

Joseph M. Lutz, 430 E. 20th St., New York, N.Y., and
Louis T. Petell, 12 Wilber St., Staten Island, N.Y.

Filed Oct. 6, 1964, Ser. No. 32,051

Term of patent 14 years

(Cl. D14—6)

FIGURE 1 is a perspective view of an automobile rain guard for drive-in theaters, showing our new design,

FIG. 2 is an extended lay out view thereof,

FIG. 3 is a front elevational view of the extended form thereof,

FIG. 4 is a perspective view of another form of the invention,

FIG. 5 is a plan view of the extended form shown in FIG. 4, and

FIG. 6 is a front elevational view of the extended form.

The vehicle fragmentarily shown in broken lines in FIGS. 1 and 4 is included for illustrative purposes only.

We claim:

The ornamental design for an automobile rain guard for drive-in theaters, substantially as shown and described.
